SAFETY RAZOR

Diedrich Claassen, Wellsburg, Iowa; Richard Claassen, administrator of said Diedrich Claassen, deceased

Application May 20, 1938, Serial No. 208,967
Renewed December 28, 1939

2 Claims. (Cl. 30—87)

My invention relates to improvements in safety razors, and the object of my improvements is to provide an implement of this kind, disassemblable, and to receive and hold removably a flexible resilient blade between its clamping members, and with its elements relatively arranged for tilttable adjustments of the blade, and for securely locking thereof in either of its tilted adjustments.

10 Another and specific improvement is the provision of a transversely limitedly movable slide device mounted on the clamping means, having oppositely inclined terminations suitably pitched to be alternately engaged by the inner termination 15 of a removable threaded handle, to in either position of opposite inclinations of the blade, be releasably interlocked between the handle end and the inner clamping member of the device in the most favorable inclined position of the 20 blade for convenient and safe employment thereof in shaving.

My invention is illustrated in the details and the combination of its elements in the appended drawing, and as described and claimed in the 25 specification and claims.

Fig. 1 is an elevation of my safety razor as assembled, and Fig. 2 is a like elevation thereof showing its parts connected but slightly separated from each other, both figures having parts broken 30 away. Fig. 3 is an elevation of the outer clamping plate with its hinged stem. Fig. 4 is a plan view of a razor blade shaped to be associated with and clamped between the clamping plates. Fig. 5 is an under plan representation of the 35 outer clamping plate. Fig. 6 is an under plan of said blade as mounted on the outer clamping plate. Fig. 7 is an under plan view of the assembled clamping plates and blade therebetween, showing the transversely movable and oppositely 40 inclined locking member on the under clamping plate.

The illustrations show a razor of the well-known Gillette type, but it is to be understood that my improvements hereinafter described may, with 45 any slight modification, be applied to other safety razors whose clamping parts are disassemblable.

The blade clamping means consists of the usual curvate outer end plate 1 and the under plate 8 conformable thereto but somewhat differently 50 shaped. The plate 1 as shown in Fig. 3 endwise, has a medial or central depending lug 2 to which a depending threaded stem 4 is hinged, and the plate has a pair of elongated stops or lugs 7 on its underface medially, the plate having at each corner small angular depending lugs 55

or stops 1a. In Fig. 6, the blade 5 of Fig. 4 is shown as mounted on the under face of the upper plate 1, fitted between the stops 1a and having a medial longitudinal aperture 6 with terminal socket ends 5a, the ends of the aperture at 5a being traversed by the longitudinal lugs 7, and the hinged stem 4 traversing the middle part of the aperture 6.

The upper face medially of the under plate 8 is longitudinally tabular to seat the flat but resilient blade 5 thereupon, as indicated in Fig. 2, and the stem 4 traverses a medial hole in said plate loosely as shown in Fig. 7. In the lower face of the under clamping plate 8 in its median line but crossing the same transversely is a shallow depression 8b in which is seated a transverse body 11 for limited to and fro movements slidably thereacross. Stop plates 9 are secured by screws 10 on a longitudinal medial rib 8c to loosely end engage their end parts medially of 20 the body 11, the latter slidable to and fro therebetween in the socket 8b. This body 11 is longitudinally troughed with inwardly sloping end walls and a central opening as a loose bearing for the traversing stem 4. A handle 14 has an inferiorly threaded socket 14a at its upper end with which the depending threaded termination of the stem 4 is meshed removably as shown in Figs. 1 and 2. The lower end of the body 11 is pitched at 11a and 11b oppositely at each side 30 of the medial widened seat therein, the latter permitting the stem 4 to rock therein limitedly transversely to the clamping plates. The handle 14 has at its upper end an inwardly beveled widening at 14b, cupped to clear the medial angles of the body 11 when the handle is turned to clear them loosely while shifting the clamping members from one side to the other tiltably.

The lower clamping plate has the usual guard fingers 8a along its opposite longitudinal edges. The lugs 7 on the upper plate 1 are to be seated in 40 medial longitudinal grooves 8d in the ribbed part 8d of the lower plate 8, to prevent relative displacements of the plates 1 and 8, rockingly.

Fig. 2 shows the different elements loosely connected together and in medial alinement. In Fig. 1, the elements are engaged clampingly throughout for use. It will be understood, that with the elements loosely engaged as in Fig. 2, and the clamping plates tilted in either direction, 50 the handle 14 may be rotated progressively to engage the face 11a or 11b in its path while drawing the clamping plates together. The plane of each face 11a, 11b so engaged being flat, the clamping plates having been initially tilted 55

sidewise, the locking of the parts is positive, affording no possibility of relative displacements without a rotation of the handle oppositely to become disengaged from the body plane previously used. Possibility of an injury to the user by rocking or other relative displacements of the clamping members and blade is thus avoided.

I claim:

1. In a safety razor, an apertured blade, a pair of clamping plates therefor, one plate having an aperture, the other plate having a hinged terminally threaded stem loosely swingable transversely and traversing the apertures in the first plate, and in said blade, an apertured slide mounted for limited to and fro movements transversely of said one plate with said stem traversing its aperture to project therefrom and with the free end of said slide shaped with oppositely pitched faces, and a handle terminally interiorly threaded to be detachably mounted on said

threaded stem, and when turned in one direction to engage the termination of said slide to swing the slide laterally, locking the handle in engagement with the plane thereof at that side, securing all said elements together rigidly and releasably.

2. In a safety razor, clamping plates for an interposed blade separably engageable between the plates, a handle, and a body transversely slidable adjustably mounted on and interlocked with the adjacent clamping plate and having a pitched termination extending toward the handle, and the handle being removably rotatable and the plates rockably mounted on the handle, whereby when the handle is rotated in one direction, the plates having been previously tilted, the handle clampingly engages the abutting face of said pitched termination.

DIEDRICH CLAASSEN. 20
